(57) **CLAIM**

The ornamental design for a plyometric box, as shown and described.

DESCRIPTION

FIG. 1 is a top, front, right perspective view of a plyometric box showing my new design;

FIG. 2 is a bottom, front, right perspective view thereof;

FIG. 3 is a front view thereof;

FIG. 4 is a right side view thereof;

FIG. 5 is a rear view thereof;

FIG. 6 is a left side view thereof;

FIG. 7 is a top view thereof; and,

FIG. 8 is a bottom view thereof.

The broken lines immediately adjacent to the shaded area define the bounds of the claimed design and form no part thereof. The broken lines depicting the remainder of the plyometric box show features that form no part of the claimed design.
